COILING MACHINE

William S. Adams, Great Falls, Mont., assignor
to Anaconda Wire & Cable Company, New
York, N. Y., a corporation of Delaware

Application February 6, 1937, Serial No. 124,364

4 Claims. (Cl. 242—84)

My invention relates to a method and apparatus for coiling metal rods and wires, etc.

Heavy metal wire, cable and rod, which is generally wire having a diameter of about $\frac{5}{8}$ of an 5 inch or more, have a considerable stiffness or resistance to bending. If wrapped about a form, to form coils, or if drawn into the form of coils by a rotating form, a considerable sidewise bending is required, which may result in stresses in the 10 finished coil that are troublesome and undesirable.

In my present invention, the wire or rod is formed into coils without wrapping it about a form, but by causing it to move gradually from 15 a longitudinal movement into a circular movement at approximately the same speed, so that it will fall naturally into the circular shape required to form the coils. The rods, wires or cables may be of any cross sectional shape and 20 of any dimension which permits forming into coils.

In forming the coils, the wire or rod is fed or pushed through a suitable guiding means tangentially into an annular channel rotating at a 25 peripheral speed corresponding to the linear speed of the wire or rod as it enters the channel. The linear speed of the rod or wire is thus transformed without change and without tension or pull into a circular speed, which causes the wire 30 or rod to fall into the form of a coil. When a coil of sufficient size has thus been built up, it may be removed from the channel. Preferably, the channel is horizontal and rotates about an upright or substantially vertical axis. The bottom 35 of the channel, on which the coil is supported as it is built up, is formed of plates hinged inwardly of the inner wall of the channel, so that they may be swung downwardly to permit a completed coil to fall out of the channel, whereupon 40 the plates may be closed for the building up of a succeeding coil.

The various features of my invention are illustrated by way of example in the accompanying drawings, in which—

Fig. 1 is a vertical axial section of a preferred embodiment of the invention; Fig. 2 is a vertical section similar to that of Fig. 1, but on a larger scale, of the receiving channel, showing the door 45 closed in full line position and open in broken lines to permit a coil to drop to the position shown in broken lines; Fig. 3 is a detail vertical section view of a part of the annular channel showing guide rollers; Fig. 4 is a plan view on the plane 50 of Fig. 1 and Fig. 5 is a detail vertical sec-

tion of a part of the coil-forming channel showing an anti-friction bearing therefor.

As shown more particularly in Figs. 1 and 2 of the accompanying drawings, a wire, rod or cable 10 is supplied through a downwardly sloping 5 guide 11 tangentially into an annular channel formed between an outer wall 12 and an inner wall 13. The inner wall 13 is inwardly flanged at 14 and secured, as by bolts 15, to a downwardly and outwardly or bell-shaped supporting structure 16. The supporting structure 16 is in turn secured by a bolt 17 to the flange of a hollow collar 18 journaled in a supporting bracket 19 extending upwardly from a base 20. The bracket 19 is provided with guide and thrust bearings 21 15 and 22, in which the collar 18 revolves. The collar 18 and with it the member 16 and inner wall 13 are rotated by a drive shaft 23 through the bevel gear 24 on the shaft and the bevel gear 25 on the collar. The speed of rotation is such 20 as to correspond with the linear speed of the rod or wire 10.

The outer wall 12 is provided with a projection 26 which is rotatably supported on a supporting ring 27, bolted as at 28 to the upright bracket 19. 25 The outer wall 12 is thus free to rotate with the inner wall 13. A covering flange 28' of angular cross-section may be mounted on the angular projection 26 to overlap and cover the upper edge of the ring 27. Horizontal rollers 29 are journaled between upper and lower lugs 30 and 31 at intervals about the periphery of the ring 27 to guide the outer wall 12 and thus insure a uniform or substantially uniform space between the inner and outer walls. An anti-friction bearing 30 consisting of balls 32 between upper and lower raceways 33 and 34 and spaced by spacing rings 35 may be employed to support the wall 12 on the ring 27, as shown more particularly in Fig. 5. 35

As the rod or wire 10 is pushed or fed into the 40 annular channel formed between the inner and outer walls 13 and 12, its direction of travel changes from a linear to a circumferential direction, but without change of speed, so that it 45 curves to a circular formation in successive turns to form a coil 36. The coil 36 in process of formation is supported by a number of horizontal plates 37 hinged at their inner edges by means of pintles 38 to brackets 39 on the lower inner surface of the wall 13. The bottom plates 37 extend 50 radially outwardly to the lower edge of the outer annular wall 12, which they meet, preferably in a conical or pyramid form 40. The plates 37 are normally held in their horizontal, supporting position by means of links 41 extending radially 55

from radial brackets 42 on the lower part of a vertical collar 43 to depending brackets 44 extending downwardly from the supporting plates 37.

5 This construction is such that downward thrust on the plate 37, due to the weight of the coil 36, is transmitted as a longitudinal compressive stress in the link 41 and thus to the bracket 42. The bracket 44 may be of a trussed 10 construction, as shown in Figs. 1 and 2, in order to impart strength and rigidity to it and to its connection with the plate 37. It will be apparent that when the collar 43 is in the position shown in full lines in Figs. 1 and 2, the thrust on 15 the link 41 will be radially inward, thus providing a very rigid and solid support for the plates 37. When the collar 43 is drawn upwardly to the position shown in broken lines in Fig. 2, the links will pull the door 37 open, as indicated in broken 20 lines and permit the completed coil to drop in the direction indicated by the arrows.

The collar 43 is moved upwardly and downwardly for closing and opening the plates 37 by means of a vertically movable piston rod 45 that 25 extends upwardly through a depending guide 46 and a hollow inner bearing 47 in the collar 18 to a piston 48 within a cylinder 49. The piston and piston rod 48, 45 may be stationary during the rotation of the collar 18 and the annular channel 30 formed by the walls 12 and 13 and the collar 43. The collar or sleeve 18 and the collar 43 are, therefore, rotatable relatively to the piston rod 45.

An anti-friction thrust bearing 50 is preferably provided between a flange 51 on the lower 35 part of the rod 45 and a shoulder 52 on the collar 43 and a cap 53 on the latter. This permits the collar to rotate freely on the rod 45 and enables upward and downward movements of the rod 45 to be transmitted to the links 41 to 40 open and close the bottom plate 37. The upward and downward movement of the piston rod 45 is accomplished by fluid under pressure to the piston 48 through the pipes 54 and 55, respectively.

Through my invention, rod and heavy or stiff wire, such as copper or other metal wire are 45 caused to assume the circular curvature and form into coils without applying any bending agencies to the rod or wire. The wire thus falls into smooth uniform turns and lies in a natural 50 position in the coil.

What I claim is:

1. Apparatus for coiling rod, wire and the like which comprises an inner circular wall, means for rotatably suspending and driving said wall, an 55 outer wall coaxial with said inner wall and spaced

therefrom to form an annular channel, plates hinged at their inner edges to the lower part of said inner wall and extending from the lower parts of said inner to said outer annular wall, said plates having depending brackets, means 5 slidable vertically coaxially of said annular walls and links extending substantially horizontally from said depending brackets to said vertically movable means to hold said plates in horizontal position and to permit said plates to swing downwardly when said means is moved vertically.

2. Apparatus for coiling rod, wire and the like which comprises an inner circular wall, means for rotatably suspending and driving said wall, an outer wall coaxial with said inner wall and spaced therefrom to form an annular channel, plates hinged at their inner edges to said inner wall and extending below said inner wall to said outer wall to support a coil of wire between said walls, said plates having depending brackets, 20 bracket supporting means slidable vertically on said suspending means and links connecting said depending brackets to said vertically movable supporting means and being substantially horizontal when said hinged plates are in horizontal 25 position.

3. Apparatus for coiling rod, wire and the like which comprises an inner wall of inverted, frusto-conical shape, means for rotatably suspending and rotating said wall on a vertical axis, an outer 30 wall coaxial with and rotatable with said inner wall and spaced therefrom to form a downwardly flaring annular channel, plates hinged to said inner wall and extending horizontally to said outer wall, said plates having depending brackets, 35 a vertical shaft coaxial with said inner wall and links connecting said shaft to said depending brackets and being substantially horizontal when said hinged plates are in horizontal position.

4. Apparatus for coiling rod, wire and the like 40 which comprises an inner circular wall, means for rotatably suspending and rotating said wall on a vertical axis, an outer wall coaxial with and rotatable with said inner wall and spaced therefrom to form an annular channel, plates hinged to the 45 inner side of said inner wall and extending below said wall horizontally to the lower edge of said outer wall, said plates having depending brackets, a vertical shaft coaxial with said inner wall and links connecting said shaft to said depending 50 brackets and being substantially horizontal when said hinged plates are in horizontal position and pneumatic means for moving said shaft vertically.
